UNITED STATES PATENT OFFICE.

ALFRED C. STEWART, OF LOS ANGELES, CALIFORNIA.

HYDRAULIC JACK FOR WELL-CASINGS.

1,100,204.

Specification of Letters Patent. Patented June 16, 1914.

Application filed February 6, 1912. Serial No. 675,868.

To all whom it may concern:

Be it known that I, ALFRED C. STEWART, a citizen of the United States, residing at Los Angeles, in the county of Los Angeles and State of California, have invented a new and useful Hydraulic Jack for Well-Casings, of which the following is a specification.

The main object of the present invention 10 is to provide means for giving a positive definite feed to the drilling tool of a well drilling machine.

A further object of the invention is to provide improved means for raising or lowering the drilling or well casing.

A further object of the invention is to provide improved means for operating the elevator and gripping devices to enable the attachment of additional sections of the casing.

Other objects of the invention will appear hereinafter.

The accompanying drawings illustrate an embodiment of the invention, and referring thereto:

Figure 1 is a vertical section of the apparatus. Fig. 2 is a plan of the apparatus partly in section, on line $\alpha^2-\alpha^2$ in Fig. 1. Fig. 3 is a section of a portion of the apparatus showing position of the parts for attachment of a new section of casing. Fig. 4 is a side elevation, partly broken away, of the controlling valve. Fig. 5 is a section on line $\alpha^5-\alpha^5$ in Fig. 4.

The invention is shown as adapted for use in connection with a rotary drilling rig such as shown in my application, Serial No. 665,390, filed December 6th, 1911. Some features of the invention are, however, applicable to any rotary or other drilling rig.

The well casing consists of a number of sections 1, connected by collars 2, to form a continuous tube which is lowered into the ground as the drilling proceeds, and the main purpose of the invention is to provide 45 means for positively feeding this casing downwardly at a definite rate of speed. This casing may be the usual well casing, or, as shown in my former application, it may

form the support for the drilling tool, so that as the said casing is forced downwardly, the drilling tool is also forced downwardly, thereby giving a positive feed to the drill. Thus in Fig. 1, the drilling tool indicated 55 at 4 is mounted on the lower end of the casing 1, and is adapted to be operated by a

shaft 5 extending vertically within the casing 1, and provided with driving means hereinafter set forth. A gripping means 7 for engaging the casing is provided, consisting, for example, of two half-ring members adapted to embrace the casing sections 1 and connected to suspending links 8, in the usual manner of a casing elevator, so as to hold the said gripping means in position in which it closely surrounds the casing sections 1 and extends beneath the top collar 2 thereon. An upper ring 10 may be provided, engaging with the top of the said top collar 2 and connected to the gripping means 7 by bolts 11, so as to grip the said top collar tightly between the said members 7 and 10, and connect the casing to the gripping means for both upward and downward operations of the gripping means.

Hydraulically operated means are provided for raising and lowering the gripping means 7. For this purpose a piston rod 12 is provided at each side of the well casing and is connected to a piston 13 slidably vertically in a cylinder 14, said piston rod being provided with means for engaging the gripping means 7 aforesaid. Cylinders 14 are rigidly mounted in the base 3 of the apparatus. In order to enable the piston rod 12 to be operated independently of said gripping means when desired, a detachable connection is provided, consisting of a yoke 18 having upper and lower slotted heads 19 adapted to embrace a reduced portion 20 of said piston rod, and to engage respectively, a head 21 on the upper end of the piston rod, and a shoulder 22 on said piston rod. Said reduced portion 20 of said piston rod extends through a vertical channel 24 in the gripping member 7, said channel being of sufficient diameter to enable free passage of the piston rod therethrough, when the yoke 18 is removed.

Pipes 26 and 27 lead respectively from the upper and lower part of each cylinder 14 to ports 28 and 29 in a valve casing 30, said valve casing being provided with two other ports 31 and 32 communicating respectively by pipes 31' and 32' with the inlet and outlet of a pump 33, operated by a shaft 34 journaled in bearings 34' and provided with suitable driving means such as stepped pulley 35. The plug 36 of the aforesaid valve is provided with an operating handle 37 and has internal passages 38 and 39 for establishing communication between the sev-

eral ports aforesaid, as hereinafter set forth, and is also provided with a passage 40 for establishing communication between the port 29 and a port 42 in the valve casting 30, said port 42 communicating through pipe 43 with a pipe 44 leading to a tank 45. Said tank 45 is normally supplied with operating liquid by means of a pump 48 pumping oil into pipe 44 from a pipe 49 leading to a reserve tank 50.

10 The operation is as follows: Assuming that the casing is in place in the well and that it is gripped by the gripping means 7, which is connected to the piston rods 12 by the yoke means 18, the drilling may proceed by rotation of the shaft 5. The rotation of said shaft 5 operates the drilling means 4 at the bottom of the casing, and as the drilling proceeds, the casing is lowered, so as to feed the drilling tools positively by operation of the hydraulic means. In this operation the valve plug is turned to position shown in full lines in Fig. 6, so that liquid is forced by pump 33 through pipe 32', port 32, passage 39 of the valve plug 36, to port 28, pipe 26 to the top of each cylinder 14, and from the lower part of each cylinder 14 the liquid passes through pipe 27, port 29, passage 38, in the valve plug, port 31 and pipe 31', back to the intake of the pump 33. The operation of the pump 33 by the driving means 35, therefore produces a gradual, positive, downward feed of the pistons 13, the piston rods 12 connected thereto, the gripping means 7, the casing 1 and the drilling means 4 at the bottom of the casing. If, on the other hand, it is desired to withdraw the casing, the operation is reversed by turning the valve plug 36 to position, in which 30 passage 38 communicates with ports 31 and 28, and passage 39 communicates with ports 29 and 32, thereby reversing the connection of the pump 33 to the cylinders 14 and causing the liquid from the pump 33 to be forced into the lower part of the cylinders and withdrawn from the upper part of the cylinders, thereby raising the pistons 13, piston rods 12, gripping means 7 and the casing. In normal operation, the pump 48 40 forces the liquid from the reservoir 50 to the pressure tank 45 which is located at considerable height, for example, at the upper part of the derrick. When it is desired to add a new section of casing, the gripping means 7 is lowered with the casing until it rests on a part 73 of base 3, beneath the same and the connecting yokes 18 are then knocked out, leaving the gripping means free of the piston rods 12. Another casing 50 section is then screwed into the collar 2 at the upper end of the casing already in place and another collar 2 is screwed onto the casing section so placed. Another gripping means 7 is then placed around the casing, below the topmost collar with its channels 24

directly above the piston rods 12. The valve plug 36 is then turned to position in which the passage 40 therein comes into register at one end with the port 29, and at the other end with the port 42, communicating with the pressure tank 45, through pipe 44. The liquid will then run from said pressure tank 45 to the lower part of the cylinders 14 causing the pistons in said cylinders to rise rapidly to the upper end of their stroke and raising the upper ends of the piston rods 12 to an extent substantially equally to the length of one casing section as shown in Fig. 4, and when the piston rods are forced upwardly as stated, their upper ends pass through the channels 24 in the upper gripping member 7 and the connecting yokes 18 may then be driven into place so as to engage with the heads 21 and shoulders 22 on the piston rods 12 and with the gripping means 7 to firmly connect said parts. The apparatus is then ready for another lowering operation. It will be understood that in case the rotary drilling apparatus with the central shaft 5 is employed, the shaft must be disconnected during this operation.

What I claim is:

1. The combination of casing gripping means, cylinder and piston means connected to operate said gripping means vertically, means for supplying liquid to said cylinder and piston means for raising or lowering said gripping means, and means detachably connecting said piston means with said casing gripping means to enable operation of the casing gripping means by the piston means when connected thereto and to permit the piston means to be raised independently of said gripping means for the purpose set forth.

2. The combination of casing gripping means, cylinder and piston means connected to operate said gripping means vertically, means for supplying fluid to cylinder and piston means for raising and lowering said gripping means, means detachably connecting said piston means with said casing gripping means to enable operation of the casing gripping means by the piston means when connected thereto, and to permit the piston means to be raised independently of said gripping means, and means independent of the aforesaid fluid supply means for supplying fluid to the said cylinder and piston means when the piston means is disconnected from the casing gripping means.

3. The combination of casing gripping means, cylinder and piston means connected to operate said casing means vertically, a pump and a valve connected thereto and to said cylinder and piston means to supply liquid from said pump to said cylinder and piston means for raising or lowering said gripping means by operation of the pump, a pressure tank, means supplying liquid to

said pressure tank, and valve controlled communicating means from said pressure tank to said cylinder and piston means to cause said piston means to be raised by 5 liquid from said tank, and means detachably connecting said piston means with said casing gripping means, to enable operation of the casing gripping means by the piston means when connected thereto and to permit 10 the piston means to be raised independently

of said gripping means for the purpose set forth.

In testimony whereof, I have hereunto set my hand at Los Angeles, California this 29th day of January, 1912.

ALFRED C. STEWART.

In presence of—

ARTHUR P. KNIGHT,
GLADYS RUSSELL.
